UNITED STATES PATENT OFFICE.

MORRIS ARONSON AND WILLIAM BAUMGART, OF NEW YORK, N. Y.

EMBROIDERING MACHINE ATTACHMENT.

Application filed August 15, 1922. Serial No. 532,032.

To all whom it may concern:

Be it known that we, MORRIS ARONSON and WILLIAM BAUMGART, both citizens of the United States, and residents of the city of 5 New York, borough of the Bronx, in the county of Bronx and State of New York, have invented new and useful Improvements in Embroidering Machine Attachments, of which the following is a full, clear, 10 and exact description.

This invention relates to embroidering machine attachments.

Embroidering machines are usually provided with means for regulating the length 15 of the embroidering machine stitches. Ordinarily, in embroidering any pattern this means for regulating the length of the embroidering machine stitches is manually operated in order to follow the pattern. If 20 an operator is not expert the pattern will not be followed with great accuracy, and even expert operators experience great difficulty in preventing certain irregularities in the work. This is due to the fact that in 25 shifting the means for regulating the length of the embroidering machine stitches manually the operator is apt to move the regulating means too far or not far enough.

The general object of this invention is 30 the provision of a simple and efficient means for shifting the means for regulating the length of the embroidering machine stitches which is operated mechanically and eliminates the inaccuracy of manual control.

This object is accomplished by designing cams for the different patterns to be embroidered, and providing means for removably mounting any cam on the embroidering machine, interposing between the cam 35 and the driving mechanism of the machine means for driving the former from the latter, and associating with the cam means operated by it for shifting the means for regulating the length of the embroidering 40 machine stitches to embroider the pattern for which the particular cam used was designed.

These and other objects of the invention will be more clearly understood from the 45 following detail description and accompanying drawings.

Figure 1 is a side elevation of an embroidering machine showing the embroidering machine attachment mounted thereon;

50 Figure 2 is a top plan view of the cam and the means for driving it;

Figure 3 is a plan view of a pattern that might be embroidered by use of the attachment;

Figure 4 is a detailed sectional view 60 through Figure 1 on line 4-4, showing the means for controlling the length of the embroidering machine stitches.

Referring to the above-mentioned drawings, an embroidering machine head is 65 shown including a casing 10 in which a main drive shaft 11 is rotatably mounted. A needle bar 12 carrying a needle 14 is slidably mounted in a sleeve 22 pivotally mounted at 22' so that as the needle bar is given 70 its vertical motion it may also be given an oscillating motion. A rock arm 15 having a groove 17 cut in one face is provided with a shaft 16 which is rotatably mounted in a bearing 21. Slidably mounted in this 75 groove 17 is a block 18 to which a curved bar 19 is pivotally attached by means of a screw 20. The arm 15 is rocked about the axis of the shaft 16 by means of a cam 23 operated through the main driving shaft. 80 Connecting the upper end of the arm 15 with the needle bar 12 through bar 19 is a rigid member 13. The rocking of the arm 15 gives the needle bar its oscillating 85 motion, and the distance through which the needle 14 carried by the needle bar 12 oscillates is controlled by moving the block 18 along the groove 17. The further that the block is moved from the axis of the shaft 16 the greater will be the oscillatory movement of the needle. If the block 90 18 is moved to any position and retained there then the figure embroidered will have parallel sides. If, however, the block 18 is moved along the groove as the machine 95 operates, stitches of different lengths will be taken so that different patterns may be embroidered. The usual machine is provided with means for manually operating the block to control the length of the stitches and to vary them so as to embroider patterns of different shapes and sizes. A suitable feeding mechanism is also provided 100 which may be the usual feeding foot now in common use. In setting forth the above machine it is not intended that it shall be included in the invention but merely in order that the operation of the embroidering machine attachment may be more clearly explained.

Rotatably mounted in the casing 10 of the head is a shaft 33. Attached to one 105 110

end of this shaft is a disk 24 carrying a plurality of cams 25, 26 and 27. These cam members are designed for a certain particular pattern. Extending around the cam members and attached to the disk is a wall 28. Attached to the other end of the shaft 33 is a worm gear 35. A shaft 37 carrying a worm 36 is rotatably mounted in bearings 38 and 39 attached to the casing 10. This shaft extends through the casing 10 and is supported by a bracket 48. Attached to the outer end of the shaft 37 is a pulley 40. A pulley 49 is mounted on the main drive shaft 11 and connected with the pulley 40 by means of a belt 50. Motion is transmitted from the main drive shaft 11 through the pulley 49, belt 50, pulley 40, shaft 37, worm 36, worm gear 35, shaft 33 to the disk 24. A curved arm 30 is rotatably mounted on a pin 31 carried by a bracket 29 attached to the table 34 of the embroidering machine. A bell crank is formed by attaching two arms 43 and 46 to the pin 44 carried by a bracket 45. Motion is transmitted from the arm 30 to the arm 43 through the pitman rod 41 which is normally retained in its downward position by means of the spring 42, one end of which is attached to the casing 10 and the other to the pitman rod 41. A rigid link 47 is provided for connecting the outer end of the bell crank to the curved bar 19. The curved arm 30 is provided with a projection 32 which extends inward toward the disk 24 and engages the cam members 25, 26 and 27. When the machine is set in operation, the disk 24 is rotated by the main shaft through the mechanism described in a preceding paragraph. As the disk rotates, the cam members move along the projection 32, rocking the arm on the pin 31. The motion of

the arm 30 is conveyed to the curved arm 19 through the members 41, 43, 46 and 47. This moves the block 18 up and down in the groove 17 as the machine operates, serving to oscillate the needle bar 12 carrying the needle 14. The oscillations are controlled by the cam members and the pattern embroidered will depend on the shape of the cam members. A pattern embroidered by such a cam is shown in Figure 3.

We would state in conclusion that while the illustrated example constitutes a practical embodiment of our invention we do not limit ourselves to the exact details herein illustrated since manifestly the same can be considerably varied without departing from the spirit of the invention as defined in the appended claim.

Claim.

In combination with an embroidery machine having a needle and driving mechanism therefor, of an attachment including a pivotally mounted arm operatively connected with said needle for varying the action thereof, a pin extending from said arm, a disk rotatably mounted on said machine, means for driving said disk from the main driving shaft of said machine, a plurality of independent cam sections mounted on said disk, each section acting to regulate the time and movement of the needle of said machine, said pin engaging said cam sections whereby the pin and arm are moved by said cam sections, and a surrounding upstanding wall mounted on said disk substantially conforming to the general shape of the cam sections and acting to prevent displacement of said pin.

MORRIS ARONSON.
WILLIAM BAUMGART.
